UNITED STATES PATENT OFFICE.

GEORGE C. CROSS, OF CLEVELAND, OHIO.

DRIVEN-WELL POINT AND STRAINER.

1,211,415.

Specification of Letters Patent.

Patented Jan. 9, 1917.

Application filed November 6, 1916. Serial No. 129,722.

To all whom it may concern:

Be it known that I, GEORGE C. Cross, a citizen of the United States, residing at Cleveland, in the county of Cuyahoga and State of Ohio, have invented certain new and useful Improvements in Driven-Well Points and Strainers, of which the following is a specification.

This invention relates to driven well points and strainers adapted for use in connection with water well pumps.

The device can be used either to drive the well or can be placed in wells made by other methods, the tubing serving as a casing for the well.

The device comprises a strainer, and a point which telescopes over the strainer, so that when used for driving the strainer is protected, but when used for pumping the strainer can be uncovered to let in water to the pump valves.

Various other features of novelty will be apparent from the following description and the accompanying drawings.

In the drawings Figure 1 is a side elevation, partly in section, of the device, in position for driving. Fig. 2 is an enlarged sectional view showing the parts in position for pumping. Fig. 3 is an end view of the upper strainer. Fig. 4 is a side view thereof, partly in section. Fig. 5 is a section on the line 5—5 of Fig. 1.

Referring specifically to the drawings, 6 indicates an upper tube section, preferably 35 lined with brass and joined to a lower tube section 7 by a screw coupling. The lower end of the tube 7 is connected by a screw coupling 9 to a strainer tube 10 having perforations, and sleeved over this tube 10 is 40 a lower tube 11 which carries the drive point 12 the shank of which is fitted into the lower end of the tube and riveted thereto as indicated at 13. To make a comparatively tight joint, a steel gland or collar 14 fits 45 in the top of the tube 11, and this collar confines keys 15 which are slidable in keyways 16 extending lengthwise along tube 10. This construction permits the strainer tube 10 to be telescoped into the sleeve tube 11 when driving. An inner tube 17 is fastened at its lower end within the tube 10 by 50 means of a collar or shoulder 18 and counter-sunk screws 19, and this inner tube receives the upper strainer for pumping, the collar 18 closing the space at the bottom of the inner tube. Said upper strainer consists of

a perforated tube 20 to which the lower pump valve casing, indicated at 21, may be attached. The perforated part of the tube 20 is surrounded by a cage consisting of 60 rods 22 set in rings 23 at the top and bottom and covered by a fine screen 24, and when assembled the lower end of the tube 20 fits in the upper end of the tube 17, as shown in Fig. 2, a tight joint being formed 65 by a gasket 25 the inner edge of which also sets into a groove at 26 in the pipe 20 to hold the parts in proper position.

In the use of the device for driving, the parts shown in Fig. 1 are employed, and 70 the tube 10 telescopes into the lower tube 11, the coupling 9 striking against the steel collar 14, which also prevents splitting or staving of the tubes, and the outer tube 11 thus protects and covers the strainer tube 75 10, preventing the entry of dirt therein. When the well is driven, or the tube is placed in an old well, the upper strainer is lowered into the piping and fitted into the upper end of the tube 17, the lower pump 80 valve 21 being lowered therewith and set in place. Then by lifting the outer piping the strainer tube 10 is drawn up from the lower tube 11, to open the casing to the water. Or the same result may be accomplished by letting down a rod through the piping and the tube 17 to contact with the head 40 on the point 12, and by driving 85 said point down the tube 11 uncovers the strainer tube. 41 are test holes in the tube. 90

By the means described a well can be driven and the tube allowed to remain in the ground to form a casing for the strainer and pump parts which can be set in place by lowering them into the tube as above described, and during the driving operation the strainer is closed off to prevent dirt entering the pipes and clogging the same. After the upper strainer is inserted it serves 95 to strain the water before it passes to the lower pump valve. The upper strainer and the valve can be readily removed by letting down a proper tool to engage and withdraw the same, and the whole forms a combined driving and pumping outfit which is practically nonclogging. 100 105

What I claim as new is:

1. The combination with an outer lower tube provided with a drive point, of a strainer tube telescoping therein with a 110 close joint between the upper end of the lower tube and the strainer tube, a casing

- pipe connected to the strainer tube, and an inner tube secured in said strainer tube and adapted for connection at its upper end to an inner strainer and pump elements.
- 5 2. The combination of an outer lower tube having a drive point a strainer tube and a casing connected thereto, the strainer tube telescoping in the outer tube, a packed joint between said tubes, an inner tube in the strainer tube and spaced therefrom, said space being closed at its lower end, and an upper strainer connected at its lower end to the upper end of the inner tube and adapted for connection to a pump valve above.
- 10 3. The combination with a strainer tube and casing connected thereto, of an inner tube fixed within said strainer tube, and a tubular upper strainer spaced within the casing and connecting at its lower end with the inner tube and adapted for connection 20 at its upper end to a pump valve, and a drive point telescopically connected to said strainer tube said tube being open ended to permit the drive point to be operated by a rod lowered through the upper strainer and 25 the inner tube.
- 15 In testimony whereof, I do affix my signature in presence of two witnesses.

GEORGE C. CROSS.
